INTERNAL COMBUSTION ENGINE

Romeo M. Nardone, East Orange, N. J., assignor
to Bendix Aviation Corporation, South Bend,
Ind., a corporation of Delaware

Application April 10, 1940, Serial No. 328,991

1 Claim. (Cl. 60—18)

This invention relates to internal combustion engines, and particularly to mechanism associated with the engine crank-shaft to impart initial rotary movement thereto, and subsequently to be driven thereby.

An object of the invention is to provide novel mechanism of the foregoing character, adapted to be mounted on the engine crank-case in constant operative engagement with an extension of the engine crank-shaft, the arrangement being such that the engine is started by energy derived from an external source, such as a reservoir of fluid under pressure, which source may thereafter be replenished by the operation of the mechanism as a fluid pump, driven by the engine.

Another object of the invention is to provide a novel construction wherein either of two rotors, as for example the rotor of a fluid motor and the crank-shaft of an internal combustion engine, may drive the other, but wherein the speed ratio of the rotors is automatically changed whenever the driving function is transferred from one to the other.

A further object of the invention is to provide novel means for producing such automatic change in speed ratios, in a mechanism of the character indicated.

Another object is to provide a novel application of hydraulic means to an internal combustion engine, for interchange of power therebetween.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claim for this purpose.

In the drawing,

Fig. 1 is a view, partly in elevation and partly in longitudinal section, of a device embodying the invention;

Fig. 2 is a view of certain parts of the assembly of Fig. 1, in relatively different positions; and

Fig. 3 is a schematic diagram of the fluid receptacles and connections.

In the drawing reference characters 5, 6, 7, and 8 designate the supporting sections constituting the housing of the device, the sections 5 and 6 being apertured to receive bolts 11 by which the unit is attached to a circular mounting flange projecting from the engine crank-case

and surrounding the clutch elements 12 and 13, the former being slidably received in the oil sealing assembly 14 of the housing section 5, and the mating clutch element 13 being an operative extension of the engine crank-shaft.

The assembly 14 facilitates longitudinal travel of the clutch element 12 into engagement with clutch element 13, the latter having a splined link 9 engaging corresponding splines on a screw-shaft 10 which constitutes the actuating element for the longitudinal as well as the subsequent rotary movement of the clutch element 12.

A shaft 15 is rotatable within screw-shaft 10, and extends through a compound planetary gear train whose low speed end is drivably connected to said screw-shaft 10. Shaft 15 has a splined end 17 drivably connecting with the correspondingly splined recess of the engine clutch element 13; the opposite end of shaft 15 being flanged, as indicated at 19, to form the inner race of a uni-directional clutch whose outer race 21 is rotatable with the rotor 22 of the fluid motor which serves as the driving agency for the gear train during the starting phase of the cycle of operation. During subsequent running of the engine the inter-meshed gears 22 and 23 operate to pump fluid back to the reservoir, or pressure accumulator 127 (Fig. 3); the drive path being shifted automatically from the planetary gear train to the shaft 15 by the novel means now to be described.

The means for automatically shifting the drive from the gear train to the shaft 15 includes, in conjunction with the uni-directional clutch 19, 35 21, a second uni-directional clutch 26, 27; the element 26 being shown as a circular ratchet integral with the sun gear 28 of the first stage of the gear train, and the element 27 being a mating ratchet ring that is constantly urged into 40 meshing relationship with ratchet ring 26 by reason of the provision of a series of coiled compressed springs 34 arranged at angular intervals about the circular flange 36 of outer clutch race 21; the springs bearing against the bottoms of 45 pockets 37 of the ratchet ring 27, to urge the latter to the left as viewed in the drawing.

The speed responsive portion of the automatic drive shifting means, which acts conjointly with but in opposition to the springs 34, is shown as 50 involving a set of balls 38 mounted in an annular cage 39 in such manner as to be shiftable to a limited extent in their individual retainer slots, by the action of centrifugal force thereupon as cage 39 is rotated with its carrying member 40 screwed to shaft flange 19 on which said

carrier 40 is mounted. As the balls 38 move outward from the axis of rotation of shaft 15, they are deflected to the right by the sloping peripheral surface of member 40. This deflection to the right causes balls 38 to exert a correspondingly directed pressure upon a flat annular portion of the ratchet ring 27, thereby moving the said ratchet ring 27 to the right, notwithstanding the opposition of springs 34. The condition of engagement as between ratchets 26 and 27 is thus discontinued, automatically, whenever the speed of shaft 15 becomes sufficient to cause balls 38 to be thrown outward and to the right, as indicated.

On the inner surface of the member 1 a plurality of (herein shown as three) sets of gear teeth are provided, as shown at 41, 42, and 43; each set being engaged by a plurality of pinions (44, 45, and 46), constituting the planets of the gear train. As shown, there are preferably three planets in each set, each planet containing a sleeve bearing (as at 47) facilitating free rotation about the corresponding one of the stub shafts (48) by which each is secured to an arm (49) of the respective mounting cages, the hubs (51) of which have toothed extensions constituting sun gears adapted to mesh with the succeeding set of planet pinions. The last set of stub shafts 48, however, are secured to a barrel 52 rotatable in housing section 6 and containing the multiple disc clutch 53.

As shown, the disc clutch 53 comprises a plurality of inter-leaving discs alternately splined to the inner surface of the barrel 52 and the outer surface of a shell 54 internally threaded to engage corresponding threads 56 on the screw-shaft 10, heretofore referred to. Resilient means, such as a plurality of coiled compression springs 57, the pressure of which is adjustable by a nut 58 threadedly engaging the end of the barrel 52, are provided to press upon a ring 59 surrounding member 54, and thus maintain the discs 53 in frictional engagement with a pressure sufficient to insure transmission of torque from barrel 52 to shell 54, up to a predetermined capacity.

To begin the cycle of operation, valve 122 (see Fig. 3) is opened and selector valves 123 and 131 are thrown (by the common control handle 143) to positions in which conduits 125 and 126, also conduits 144 and 145, inter-communicate. Liquid under pressure then passes from accumulator 127 to the starter by way of conduits 128, 125, 126, and 121, the latter terminating in the pump housing. Rotation is thus imparted to the gears 22 and 23, and thence to the engine crank-shaft by way of the intervening ratchet elements 27, 26, the planetary gear train, the elements 52, 53, 54 and 56, and the clutch 12, 13; as heretofore indicated, the shaft 15 being rotated at the slower speed of the member 13, and the difference in speeds between shaft 15 and rotor 22 being made possible by the interposed over-running clutch 19, 21. The liquid is discharged on the opposite side of gears 22 and 23, to conduit 129, and from there to the reservoir 130, the return path including conduit 144, return flow selector valve 131, conduit 145, the shut-off valve 132, and the conduit 133.

As soon as the engine starts, the operator closes communication between conduits 125 and 126 (by appropriate shifting of valve 143) and the gears 22 and 23 now pump liquid from reservoir 130, by way of conduit 141, non-return valve 142 and conduits 120 and 121, and deliver the pumped liquid to the accumulator 127, by way of conduit 129, conduit 152, non-return valve 153, and conduit 154. This delivery replenishes the supply of liquid under pressure in accumulator 127, so that the latter may continue to serve the needs of the entire hydraulic system, not only during continued operation of the engine, but also during subsequent starting thereof. During this pumping phase of operation the drive from engine member 13 to the pump gear 22 is by way of shaft 15, hence at a one-to-one ratio, for the clutch element 12 is automatically retracted (to the position indicated in Fig. 1) and therefore there is no rotation of the planetary gear train by the engine; and as the speed of rotation of shaft 15 is the same as that of engine member 13, it follows that there will be sufficient centrifugal force to hold balls 38 in the "outer" position (Fig. 2) thereby preventing any possible return of ratchet element 27 to the engaging (gear driving) position shown in Fig. 1, until such time as the engine stops, whereupon the decelerating balls 38 will be thrust back (by springs 34) to the position shown in Fig. 1, thus carrying the ratchet element 27 back into engagement with teeth 26, so that the parts are in position for the next engine starting operation.

35 The threads 56 of screw-shaft 10 are shown as terminating at the neck portion 55, which neck portion thus provides a surface engageable with the shoulder of shell 54 to stop the longitudinal travel of the screw 10 when the parts 12 and 13 have been fully meshed. This feature of construction of the screw 10 and shell 54 is claimed in my application No. 362,272, filed October 22, 1940.

40 Although the clutch elements 26, 27 are shown as ratchet elements, any other form of disengageable clutch may be substituted, as the use of uni-directional driving faces, at this point in the assembly, is not essential. Likewise other changes may be made in the construction and 45 inter-relationship of the parts, to the extent permitted by the scope of the appended claim. Related subject matter is disclosed in my application No. 319,955 filed February 20, 1940.

50 What is claimed is:

55 In combination with an internal combustion engine and a source of liquid under pressure, means including a pump operable to cause flow of liquid under pressure, first, from said pressure source, and secondly, to said pressure source, 60 means forming a driving connection for rotation of the engine by the pump, and means driven by the engine for continuing the rotation of the pump in the same direction after the engine reaches a normal running speed, said last-named means further operating to cause cessation of 65 movement of said first-named driving connection.

ROMEO M. NARDONE.
